UNITED STATES PATENT OFFICE.

CLEMMA R. RANEY, OF RIVERSIDE, ILLINOIS, ASSIGNOR TO INTERNATIONAL HAR-
VESTER CO., A CORPORATION OF NEW JERSEY.

GRAIN SHOCKER.

Application filed July 23, 1923. Serial No. 653,111.

My invention relates to shocking machines, and more particularly to a device for properly building and forming a shock.

One of the objects of the present invention is to provide a device for properly positioning and compressing the sheaves in a shock prior to binding the shock and setting the same upon the ground.

A further object is to provide a device in which certain sheaves in the shock are shifted with respect to the other sheaves.

A still further object is to provide a device which will not only properly position the sheaves in the shock receptacle but will also compress the heads of the shock in such a manner as to form a symmetrical and pointed shock which will readily shed water.

I attain these and other objects by providing an improved sheaf positioning and compressing means cooperating with the sheaf delivery member of the shocker whereby the upper or top sheaves are shifted rearwardly with respect to the lower sheaves, and at the same time the head of all the sheaves are compressed in such a manner that all the sheaves occupy a position in the receptacle conductive to the building of a compact shock tapered to a point at the head and capable of standing in the field under all weather conditions.

In the accompanying drawings I have illustrated one embodiment which my invention may assume in practice.

It is to be understood, however, that the form shown herein may be modified.

Figure 1 is a side elevational view of a standard type of grain shucker embodying my improved shifting and compressing mechanism therein;

Fig. 2 is a front elevational view showing my improved sheaf shifting and compressing mechanism positioned on the opposite sides of the shock receptacle and also showing in full and dotted lines two positions to which the sheaf delivery member is adapted to be swung in its lateral movement in depositing the sheaves from the binder deck of the harvester to the receptacle of the shucker;

Fig. 3 is a side elevational view of the shield and compressor arm positioned on the knotted side of the grain shucker; and

Fig. 4 is an enlarged detail view partly in

section showing the construction of the shifting and compressing members.

In the construction I have illustrated a shocker of a standard type comprising the main frame 10 mounted on carrying wheels 11 having a sheaf delivery member or fork 12 pivoted thereon at 13 and operated through a power shaft 14 from any suitable source of power, the rotation of the power shaft 14 being transmitted to the sheaf delivery member 12 through the cranks 15 and 16 and a resilient pitman connection 17 in such a manner that as the shaft 13 is rotated the member 12 is moved alternately back and forth from the dotted line position to the full line position shown in Fig. 1 to receive and deliver the sheaves to a shock receptacle 17'. As in the standard construction, suitable tripping mechanism 18 is provided to control the connection of the shock binding needle 19 to the power shaft 14, a cam 20, a member 21, movable with the sheaf delivery member, and means 22 actuated thereby but connected to the clutch through the tripping mechanism 18 and control the same in a well known manner. Also, as provided in the standard construction, the two-to-one gears 23 and 24 respectively are driven from the power shaft 14, the gear 24 being connected through a link 25 swiveled to said gear and to a vertically disposed shaft 26, which has a horizontally disposed crank 27 formed integrally therewith for oscillating a bail member 28 which laterally deflects the fork or sheaf delivery member 12 by means of the guide rollers 29 positioned on the opposite sides of the bail member. The fork 12 in the course of delivering sheaves to the receptacle is deflected alternately from the full line position to the dotted line position shown in Fig. 2, and in the manner described and claimed in my U. S. Letters Patent No. 1,242,112 of October 2, 1917.

The shock supporting frame comprises the usual U-shaped frame member 30 fixed to the main frame 10, and in turn supports a transversely inclined bar 31. The grassward end of the bar 31 (see Fig. 2) is fixed to a rearwardly extending brace 32, which supports a channel bracket 33 on which one of the carrying wheels 11 is mounted. The stubbleward end of the bar 31 is connected

through a bearing bracket 34 to a rearwardly extending side frame member 35 to which is attached a diverging brace 36 for supporting the channel bracket 37 on which the other carrying wheel 11 is mounted. An additional rearwardly extending side frame 38 is provided and is connected at its forward end to the cross bar 31, and at its rear end to a vertical frame member 39. The frame member 38 supports a breast or knotter plate 40 and a compressor arm 41.

My improved device for shifting and compressing the sheaves of each shock prior to binding the shock comprises a pair of oscillating sheaf compressing and shifting members 42 and 43 disposed on the opposite sides of the shock receptacle, and preferably made of sheet steel. The sheaf shifting and compressing members 42 and 43 are substantially square in outline, and are provided with a plurality of spaced vanes 44 secured thereto by means of rivets 45. The vanes 44 are adapted to aggressively engage the heads of each of the sheaves as they are being shifted and compressed by the sheaf shifting and compressing mechanism. The sheaf shifting and compressing members 42 and 43 are secured to a U-shaped member 46 by means of bolts 47. The upper leg portions of the U-shaped member 46 are angularly disposed at 46' with respect to the lower body portion of these legs, as clearly shown in Fig. 4. The U-shaped member 46 is pivotally mounted in a bearing bracket 48 secured to the transverse bar 31 by means of bolts 49. By referring to Fig. 2 it will be seen that the U-shaped member 46, together with the sheaf shifting and compressing members 42 and 43, are so positioned and arranged with respect to the sheaf delivery member 12 that the sheaf delivery member 12 is permitted to swing laterally as well as to swing in a vertical plane in delivering the sheaves from the binder deck of the harvester to the shock receptacle of the shocker without interfering or obstructing the operation of the sheaf shifting and compressing members. The sheaf shifting and compressing mechanism is actuated to shift and compress the sheaves through a crank 53 of a bell crank member 50, which is pivotally mounted in a bearing bracket 51 secured to the main frame 10 by means of bolts 52. The bell crank 50 is provided on its grassward side with a second crank 54. The free end of the crank 54 is connected by a link 55 to the pivotal connection 56 of the crank 15 and pitman 17. The free end of the crank 53 is pivotally connected to a pitman connection 57 which extends upwardly and has its upper end resiliently connected to the sheaf compressing and shifting mechanism. This resilient connection comprises a swiveling connection 58 which is slidably mounted on the upper end of the pitman 57, and is se-

cured or held from displacement on the upper end of the pitman 57 by a washer and cotter pin 59. The swiveling connection 58 is normally pressed outwardly by a spring 60 embracing the pitman 57, and held in contact with the connection 58 by a cotter pin and washer 61. By this construction it will be seen that the connection 58 is free to slide on the pitman 57 against the tension of the spring 60, and thereby forms a resilient connection for actuating the sheaf shifting and compressing mechanism. The connection 58 is provided with a laterally extending stud 62, which in turn is pivotally connected to a bracket 63 secured to the U-shaped member 46 by bolts 64. The stud 62 is held from displacement with the bracket 63 by means of a cotter pin 65 extending therethrough. I have provided means for preventing the locking of the pitman 57 on dead center with the sheaf shifting and compressing mechanism by providing a laterally extending stop or lug 66 extending outwardly, and adapted to be engaged by the side of the connection 58. By this arrangement it will be seen that as the sheaf compressing and shifting mechanism is actuated from its full line position to the dotted line position shown in Fig. 1, it is limited by this stop or lug 66 in its downward movements, and thereby locking on dead center is prevented.

Additional means is provided for assisting the sheaf shifting and compressing members 42 and 43 in a manner to confine the heads of the tops of the sheaves in the path of movement of the sheaf shifting and compressing members. This means comprises a plurality of shields positioned on the opposite sides of the receptacle. One of these shields is shown at 67 extending vertically and secured to the side frame member 38, and braced in this position by a rod 69. The grassward side of the shock receptacle is provided with a shield 70, which is secured by means of bolts 71 to the frame member 35 and braced in its vertical position by a brace rod 72.

In the operation of the above described device, it will be noted that the sheaf shifting and compressing mechanism cooperates with and is controlled by the sheaf delivery member in such a manner that, as the sheaf delivery member 12 is returned to its normal sheaf receiving position, the sheaf shifting and compressing mechanism is oscillated first rearwardly and then downwardly as shown in Fig. 1, and then as the sheaf delivery member is actuated to deliver a sheaf into the receptacle 17 the sheaf shifting and compressing mechanism is oscillated forwardly out of the path of the sheaf delivery member. It will be noted in this connection that the shifting and compressing mechanism herein described performs two func-

tions, that of shifting the upper sheaves of the shock with respect to the other sheaves in the shock prior to the binding operation, and that of compressing the heads of all of the sheaves in the shock. The members 42 and 43 obviously will perform this dual function in their movement rearwardly and then downwardly. The sheaf delivery member is oscillated back and forth, delivering 10 sheaves into the receptacle until the number of sheaves in the receptacle has reached a predetermined height, or a height sufficient to be within the path of movement of the sheaf shifting and compressing members 42 and 43, and at which time upon the return 15 of the sheaf delivery member 12 these members 42 and 43 engage the heads of the upper or top sheaves of the shock and shift the same rearwardly, and then compress all the 20 sheaves of the shock in a manner to form a symmetrical shock prior to binding and setting the same on the ground.

While I have, in this application, specifically described one form my invention 25 may assume, it is, of course, to be understood that the form chosen for the purpose of illustration may be modified without departing from the spirit of my invention.

What I claim as my invention and desire 30 to secure by Letters Patent is:

1. A shocking machine comprising a frame, a shock receptacle carried thereby, means for delivering sheaves into said receptacle, and means for shifting the sheaves 35 in a longitudinal direction and compressing them in said receptacle.

2. A shocking machine comprising a frame, a shock receptacle carried thereby, means for delivering sheaves into said receptacle, and single means for shifting the sheaves in a longitudinal direction and compressing them in said receptacle.

3. A shocking machine comprising a frame, a shock receptacle carried thereby, 45 means for delivering sheaves into said receptacle, and movable means for first shifting the sheaves longitudinally in said receptacle and then compressing said sheaves.

4. A shocking machine comprising a frame, a shock receptacle carried thereby, means for delivering sheaves into said receptacle, and single movable means for first shifting the sheaves longitudinally in said receptacle and then compressing said sheaves.

5. A shocking machine comprising a frame, a shock receptacle carried thereby, means for delivering sheaves into said receptacle, and movable means for first shifting certain of the sheaves longitudinally in said 55 receptacle and then compressing all of said sheaves.

6. A shocking machine comprising a frame, a shock receptacle carried thereby, means for delivering sheaves into said receptacle, and single means for first shifting cer-

tain of the sheaves longitudinally in said receptacle and then compressing all of said sheaves.

7. In a shocking machine having a frame, the combination of a shock receptacle carried thereby, means for delivering sheaves into said receptacle, and means for bodily and longitudinally shifting the sheaves in said receptacle.

8. A shocking machine comprising a frame, a shock receptacle carried thereby, means for delivering sheaves into said receptacle, and single means for first shifting the sheaves longitudinally in said receptacle and then compressing said sheaves.

9. A shocking machine comprising a frame, a shock receptacle carried thereby, means for delivering sheaves into said receptacle, and means for first shifting the sheaves rearwardly in said receptacle and then compressing said sheaves.

10. A shocking machine comprising a frame, a shock receptacle carried thereby, means for delivering sheaves into said receptacle, and single means for first shifting the sheaves rearwardly in said receptacle and then compressing said sheaves.

11. A shocking machine comprising a frame, a sheaf receiving receptacle carried thereby, mechanism for positioning sheaves on the opposite sides of said receptacle, and means for longitudinally shifting certain of said sheaves in said receptacle prior to compressing the sheaves by said means.

12. A shocking machine comprising a frame, a sheaf receiving receptacle carried thereby, mechanism for positioning sheaves on the opposite sides of said receptacle, and means positioned on the opposite sides of said receptacle for longitudinally shifting and compressing the sheaves in said receptacle.

13. A shocking machine comprising a frame, a sheaf receiving receptacle carried thereby, mechanism for positioning sheaves on the opposite sides of said receptacle, and means alternatingly actuated with said mechanism for longitudinally shifting and compressing the sheaves in said receptacle.

14. A shocking machine comprising a frame, a sheaf receiving receptacle carried thereby, mechanism for positioning sheaves on the opposite sides of said receptacle, and means positioned on the opposite sides of and alternatingly actuated with said mechanism for longitudinally shifting and compressing the sheaves in said receptacle.

15. A shocking machine comprising a frame, a shock receptacle carried thereby, a sheaf delivery member mounted on said frame for alternately delivering sheaves on the opposite sides of said receptacle, and means cooperating with said sheaf delivery member for longitudinally shifting and compressing the sheaves in said receptacle.

16. A shocking machine comprising a frame, a sheaf receiving receptacle carried thereby, mechanism for delivering sheaves in said receptacle, sheaf shifting and compressing mechanism cooperating with said sheaf delivery mechanism, and means carried by said sheaf shifting mechanism for engaging the heads of the sheaves. 70
17. A shocking machine comprising a frame, a sheaf receiving receptacle carried thereby, mechanism for delivering sheaves in said receptacle, sheaf shifting and compressing mechanism cooperating with said sheaf delivery mechanism, and a plurality of vanes carried by said sheaf shifting mechanism for engaging the heads of the sheaves. 75
18. A shocking machine comprising a frame, a sheaf receiving receptacle carried thereby, mechanism for delivering sheaves in said receptacle, a sheaf shifting and compressing mechanism cooperating with said sheaf delivery mechanism, and a plurality of transversely extending vanes carried by said sheaf delivery mechanism for engaging the heads of the sheaves. 80
19. A shocking machine comprising a frame, a shock receptacle carried thereby, an oscillating sheaf delivery member for delivering sheaves in said receptacle, and means positioned on the opposite sides of the path of movement thereof for longitudinally shifting and compressing the sheaves in said receptacle. 85
20. A shocking machine comprising a frame, a shock receptacle carried thereby, an oscillating sheaf delivery member for delivering sheaves in said receptacle, and oscillating means positioned on the opposite sides of the path of movement thereof for longitudinally shifting and compressing the sheaves in said receptacle. 90
21. In a shocking machine having a frame, the combination of a shock receptacle carried thereby, means for delivering sheaves into said receptacle, and a single means for engaging and longitudinally shifting the sheaves in said receptacle. 95
22. In a shocking machine having a frame, the combination of a shock receptacle carried thereby, means for delivering sheaves into said receptacle, and means alternatingly operable with the delivery means for longitudinally shifting the sheaves deposited in said receptacle. 100
23. In a shocking machine having a frame, the combination of a shock receptacle carried thereby, means for delivering sheaves into said receptacle on opposite sides thereof, and means cooperating with the delivery means for engaging the oppositely disposed sheaves and shifting them longitudinally in the receptacle. 110
24. In a shocking machine having a frame, the combination of a shock receptacle car- 115
- ried thereby, means for delivering sheaves into said receptacle, means for bodily and longitudinally shifting the sheaves in said receptacle, and means for preventing lateral displacement of the sheaves when shifted. 120
25. In a shocking machine having a frame, the combination of a shock receptacle carried thereby, means for delivering sheaves into said receptacle, means for shifting and compressing the sheaves in said receptacle, and means carried by the frame for preventing lateral displacement of the sheaves as they are shifted and compressed. 125
26. In a shocking machine having a frame, the combination of a shock receptacle carried thereby, means for delivering sheaves into said receptacle, means for bodily and longitudinally shifting the sheaves in said receptacle, and stationary means on opposite sides of the receptacle carried by the frame for preventing lateral displacement of the sheaves when shifted. 130
27. In a shocking machine, the combination of a frame, a sheaf receiving receptacle carried thereby, a sheaf delivery member pivotally mounted on the frame, means for swinging said member to and from the receptacle, and means operatively connected to the means for swinging said delivery member for bodily shifting sheaves in said receptacle. 135
28. In a shocking machine, the combination of a frame, a shock forming receptacle thereon, a sheaf delivery member pivoted on the frame, mechanism for swinging said delivery member to and from the receptacle, and means operated by the mechanism which operates the delivery member for bodily shifting sheaves in said receptacle. 140
29. In a shocking machine, the combination of a frame, a shock forming receptacle thereon, a sheaf delivery member pivoted on the frame, mechanism for swinging said delivery member to and from the receptacle, and means controlled by the delivery member operating mechanism for shifting and compressing sheaves in the receptacle as a shock is being formed therein. 145
30. A shocking machine comprising a frame, a shock receptacle thereon, intermittently operated means for positioning sheaves in said receptacle, and intermittently operated means alternating with said first mentioned means for longitudinally shifting and compressing sheaves in the receptacle as a shock is being formed therein. 150
31. A shocking machine comprising a frame, a shock receptacle thereon, means for positioning sheaves in said receptacle, means for moving said member to and from the receptacle, means for shifting and compressing sheaves in the receptacle as a shock is being formed therein, and means connected to the means for moving the sheaf positioning means to operate said shifting and com- 155

pressing means alternately with the sheaf positioning means.

32. A shocking machine comprising a frame, a shock receptacle thereon, a sheaf delivery member pivoted on the frame, means for moving said member to and from the receptacle, means for longitudinally shifting and compressing sheaves in the receptacle, said shifting and compressing means being operated by mechanism controlled by the means which operates the sheaf delivery member in such a manner

that its operation will alternate with the sheaf delivery member.

33. In a grain shocker, the combination of a frame, a shock forming receptacle thereon, a sheaf delivery member movable to and from the receptacle, a sheaf shifting and compressing member movable to and from the receptacle, and means for operating said delivery member and shifting and compressing member alternately.

In testimony whereof I affix my signature.

CLEMMA R. RANEY.
